UNITED STATES PATENT OFFICE.

LEWIS F. WARD, OF MARATHON, NEW YORK.

IMPROVEMENT IN EXTENSION-LADDERS.

Specification forming part of Letters Patent No. **38,345**, dated April 28, 1863.

To all whom it may concern:

Be it known that I, LEWIS F. WARD, of Marathon, in the county of Cortland and State of New York, have invented certain new and useful Improvements in Extension-Ladders; and I do hereby declare that the same are described and represented in the following specification and drawings.

To enable others skilled in the art to make and use my improvements, I will proceed to describe their construction and use, referring to the drawings, in which the same letters indicate like parts in each of the figures.

Figure 1 is a plan or top view. Fig. 2 is a section.

The nature of my invention and improvements in extension-ladders consists in the combination and arrangement of devices hereinafter described and claimed.

In the accompanying drawings, A A are side pieces connected by the bars B B, and the upper bar has a pulley, C, on it for the rope to run over that raises and lowers the other sections. I fasten two boxes to the sides A A for the shaft D to turn in, which winds up the rope to raise the other sections of the ladder. The shaft D is provided with two wheels, E E, fitted to turn freely on the shaft and roll on the ground when the ladder is moved, and when it is set up the linchpins are taken out and put through the hub of the wheels and shaft, which may be turned by the crank-pins F F to wind or unwind the rope that raises the sections; and when the ladder is taken down the linchpins may be replaced in the end of the shaft and the ladder carried on the wheels. There is a ratchet, G, fastened to the shaft D, and a sliding pawl, H, to catch the teeth of the ratchet when it is turned, so as to hold the ratchet and shaft when the rope is wound up. There are some tubes, I I, fitted to the ends of the sides A A, which tubes receive the ends of the sides A' A', so as to connect them together. The metal guides J J are fastened to the sides A A, and also the guides K K, to hold and guide the upper sections as they are run up by the rope L, which is provided with a hook, M, which is hooked under the lower bar of the section to be raised, and the rope passes over the pulley C to the

shaft D, which winds up the rope and draws up the section, and there are inclined planes P P, fastened under the lower bar of the sections, which, as they pass up, press back the spring-catches P' P', and pass over them, when the catches spring out below the inclined plane and hold up the section. The lower ends of the upper sections are provided with tubes to receive and connect the ends of the sections next below, so that when one section has been drawn up by the rope L the ends of the next section may be inserted in the tubes, and the rope and hook drawn down and hooked under the lower bar, so that it may be drawn up and push up the section above it. The sides A² A² of the upper section are hinged at Q Q, so that the upper portion will lay on the roof of the house, as shown in the drawings. The ends of the bar R may form the pivots of the hinge. The sides of this ladder are the same distance apart from end to end in all the sections, and I make a car, S, Fig. 3, with wheels which run on the sides of the ladder, and the rope to draw up this car passes over the pulley T on the bar R, and over the pulley U, then down over the pulley V to the shaft D. The pulleys T and V hold the rope from the eaves of the roof. The ends Y Y of the last section raised are slanted off, as shown in the drawings, to allow the car-wheels to pass readily onto or over them, and the ends of the guides J J are so thin that the car-wheels pass readily over them. The wheels of the car should be so large, or the bars which connect the axles should be placed so high, that the car will pass readily over the bend in the ladder at the eaves.

The car S may be used to take up shingles, brick, mortar, or other materials required.

The spikes in the staples W W may be driven into the roof when the ladder is placed to hold it there.

There may be more sections in number than are shown in the drawings, so as to make the ladder the length required.

I contemplate that the tubes which connect the sections may have an inclined plane joined to them.

I believe I have described my improvements

in extension-ladders so as to enable any person skilled in the art to make and use them without further invention and experiment.

I will now state what I desire to secure by Letters Patent—

1. The inclined planes P P, in combination with the spring-catches P', for locking the sections.

2. The construction of the ladder in the manner and for the purpose substantially as described.

L. F. WARD.
